UNITED STATES PATENT OFFICE.

NORMAN COLLINS, OF LONDON, ENGLAND, ASSIGNOR TO THE EMPIRE
CASH REGISTER LIMITED, OF LONDON, ENGLAND.

CASH-REGISTER.

SPECIFICATION forming part of Letters Patent No. 694,252, dated February 25, 1902.

Application filed January 2, 1901. Serial No. 41,841. (No model.)

To all whom it may concern:

Be it known that I, NORMAN COLLINS, engineer, a subject of the Queen of Great Britain, residing at Monument Square Chambers, 5 London, E.C., England, have invented certain new and useful Improvements in Cash-Registering Machines, of which the following is a specification.

This invention relates to improvements in 10 apparatus for registering cash receipts, such as described in the specification of previous Letters Patent dated June 20, 1899, and numbered 627,403; and the improvements have for object to furnish printed records of each 15 individual amount received and of the aggregate of that and of the several amounts previously recorded, as well as a record of the time at which each transaction is registered.

The improvements also have for object to 20 insure the proper working of the apparatus under all circumstances and to prevent the falsification of the record through omission to complete the registration by printing a record of a transaction in respect of which a key 25 may have been depressed.

The improvements also have for object to enable a separate time-record to be printed without altering the cash record in order to show, 30 for example, the times of opening and closing the registering-machine for purposes of business and to provide for the use of a detector whereby to enable the approximate times of 35 inspection to be recorded. An incidental advantage is that the entire mechanism may be locked, so as to prevent the unauthorized use of the machine outside business hours.

Reference is to be had to the accompanying drawings, wherein Figure 1 is a general plan of the cash-registering machine, the 40 clock mechanism being omitted. Fig. 2 is a transverse section on line A A, Fig. 1. Fig. 3 is a right-hand end elevation of the mechanism within the casing. Fig. 4 is a left-hand end sectional elevation showing the inking 45 and printing mechanisms. Figs. 4^a and 4^b are detail views of the same. Fig. 5 is a detail of the cam mechanism for producing a sudden action in printing the records. Fig. 5^a is a side elevation, partly in section, of the 50 same. Fig. 6 is a section on line B B, Fig. 1, showing the "carrying-over" or transfer

mechanism appertaining to the type-wheels for printing the aggregate or total record. Fig. 7 is a plan of the said transfer mechanism. Fig. 8 is a front elevation of the type-wheels for printing the aggregate or total record. Fig. 9 is a section on line C C, Fig. 8, looking in the direction of arrow E. Fig. 10 is a section on line C C, Fig. 8, looking in the direction of arrow D. Fig. 11 is a section on line F F, Fig. 8, looking in the direction of arrow D. Fig. 12 is a section on line G G, Figs. 1 and 14. Fig. 13 is a section on line H H, Figs. 1 and 14. Fig. 14 is a plan of the 60 clock and time cam mechanism shown as removed from the machine.

The same reference-numerals indicate the same parts in all the figures.

The apparatus resembles that described in the specification of the previous patent aforesaid in so far that it comprises separate banks 70 of key-levers and separate spring-revolved stud-barrels, (one for each denomination of the monetary system in use,) each barrel when released by the action of a key in the 75 corresponding bank performing a complete revolution in two stages, the first partial revolution occurring when a key is depressed and corresponding in amplitude to the value of the key actuated and the complement of the 80 revolution being performed when the key rises. In the present apparatus the latter portion of the rotation of the barrel is utilized to reset the type-wheels by which the detail record is printed, and the rewinding (after 85 each operation of the barrel or barrels which have been released) is effected by the revolution of a hand-operated shaft from which the entire recording mechanism is operated or controlled instead of the rewinding being 90 performed by the depression of the key itself.

In the drawings, 1 2 3 are spring-revolved stud-barrels, to which correspond banks of keys respectively for the registration of amounts in pence, shillings, and pounds, the 95 three barrels being in axial alinement and, preferably mounted to turn about the same stationary spindle 4, the spring 5 of each barrel being attached at its inner end to a sleeve 6, turning on the spindle 4, and the barrel 100 turning upon the sleeve. Each of the stud-barrels 1 2 3 is geared directly with a type-

wheel of corresponding denomination for printing such part of the record of each individual transaction as is expressed in that denomination, the type-wheels corresponding, respectively, to the stud-barrels 1 2 3 being denoted by the figures 7 8 9 and each barrel 1, 2, or 3 determines by its partial rotation (permitted by the depression of a key in the bank corresponding to that barrel) a corresponding partial rotation of the corresponding type-wheel 7, 8, or 9, so that it will be brought to position to print a value corresponding to the value represented by the key depressed. The subsequent partial rotation of the barrel permitted by the rise of the key and forming the complement of a single revolution of the barrel effects the return of the said type-wheel to zero. For this purpose each barrel has a gear-wheel 10 fast therewith, which gears through an intermediate wheel 11 with a wheel 12, fast on the shaft 13, 14, or 15 of the type-wheel 7, 8, or 9, respectively, the gear-wheels of each set being of equal diameters, so that one revolution of the barrel produces one revolution of the corresponding type-wheel shaft. The shaft 13 of the pence type-wheel 7 passes through the shillings and pounds type-wheels 8 9 and through their shafts 14 15, which are tubular, the shaft 15 being sleeved upon shaft 14. The key-levers of all the banks are pivoted on a cross-rod 16, and the mechanism of the key-levers and stud-barrels of all the banks is similar. Each comprises a motion-transmitting cross-bar 18, which is common to the keys of that bank and is lifted when by the operation of any key in the bank the rear end 17 of that key is raised. The cross-bar 18 is carried by arms 19, pivoted on the cross-rod 16, the one arm 19 of the cross-bar frame being formed with a cam 20, engaging a stud and friction-roller on a detent-lever 21, loosely pivoted on a shaft 22 and engaging by its lug 23 with a stud 24 on the barrel 1, 2, or 3, whereby the latter is normally retained at the zero position. The barrel has peripheral studs 25 for engagement by the respective key-levers and spaced at equal angular distances around the barrel, there being a stud corresponding to each key in the bank. Each key-lever 17 is provided with a detent 26 for engagement with the corresponding stud of the barrel, said detent being formed, preferably, by a pair of plates 27, pivoted on the rod 16 and straddling the key-lever, the plates being connected by cross-studs 28 29, the one above and the other below the key-lever, so that the detent 26 will be moved by the lever with freedom for a certain amount of lost motion. The detent 26 is pressed upward by a spring 30, so that it will have a less angular movement than the key-levers, and will consequently come into the path of the corresponding stud 25 before the key-lever completes its stroke in the one direction and will remain in engagement with the stud until the key-lever has nearly completed its return stroke.

With each barrel 1 2 3 there is combined a shaft 31, 32, or 33, these shafts being sleeved concentrically one on another and serving for adjusting type-wheels 34 35 96 97, which at each operation of the machine print (concurrently with the record printed by the detail type-wheels 7 8 9) a record of the total or aggregate of previous records and of the amount which may be in course of registration. For this purpose each barrel 1 2 3 is geared with the corresponding shaft 31, 32, or 33 by means of a spring-actuated coupling which comes into action when the cross-bar 18 is raised by the operation of any key in the corresponding bank, so that at the same time that the corresponding type-wheel 7, 8, or 9 (for printing the detail cash record) is moved from zero to an angular extent corresponding to the value of the key operated the type wheel or wheels 34 35 96 97 pertaining to the corresponding denomination for printing the total cash record will be advanced to an equal angular extent from the position which it previously occupied. The said coupling comprises a gear-wheel 37, fast on the shaft 31, 32, or 33, the said gear-wheel being in axial alinement with the intermediate wheel 11, which turns loose on the same shaft 31, 32, 95 or 33. The two wheels 37 and 11 are equal and have their teeth in alinement and are sufficiently adjacent to one another to be both geared with the same broad pinion 38 when the latter is moved latterly, as hereafter described, so that at the same time that motion is transmitted from the stud - barrel through the wheels 10 11 12 to the shaft 13, 14, or 15 of the detail type mechanism an equal amount of motion will be transmitted from the same barrel through the wheels 10 11 38 37 to the corresponding shaft 31, 32, or 33 of the totalizing type mechanism. The three pinions 38 are loose on the same rod 39, which is fitted to slide longitudinally in bearings in the frame of the machine, and the three pinions 38 are each constantly in gear with a wheel 37 and are constantly pressed in the direction of engagement each with the corresponding wheel 11 by a spring 40, but are each normally held out of engagement with wheel 11 by a stop 41, engaging in a peripheral groove 42 in the boss of the pinion 38. The said stop 41 is carried by a link 43, jointed at 44 to one of the arms 19 of the cross-bar frame, and is guided by a fixed stud 45, engaging in a vertical slot 46, or otherwise, so that as soon as the motion-transmitting cross-bar 18 begins to be raised by any key of the corresponding bank the stop 41 will be disengaged from the corresponding pinion 38, which will therefore be forced by its spring 40 into gear with the corresponding wheel 11. The corresponding totalizing type-wheel shaft 31, 32, or 33 will thus be coupled to the stud-barrel before the latter is allowed to move from normal position by the release of its stud 24 from the detent 23 21 through the operation of cam 20. The coupling-pinion 38 is disen-

gaged from the wheel 11 by the operation of a cam 47, which engages with a stud 48 on an arm 49, rigidly attached to the slide-rod 39. The cam 47 is fast on shaft 22, which shaft is geared 5 with the hand-operated main or first-motion shaft 50 (upon the revolution of which the operation of the machine is dependent) through a pair of equal gear-wheels 51 52, respectively fast on shafts 50 and 22, the cam 47 effecting 10 the disengagement of the coupling-pinion 38 when the stud-barrel 1, 2, or 3, having performed the first portion of its revolution, is held arrested, (by the engagement of the detent 26 of the key-lever, which has been actuated, with the corresponding stud 25 on the barrel,) so that when the barrel is permitted to complete its rotation the corresponding totalizing-shaft 31, 32, or 33 will not be operated. This disengagement of the pinion 38 is effected 15 by a collar 53, fixed on the rod 39 and which is caused to bear against the boss of the pinion 38 and to move said pinion longitudinally, so as to compress its spring 40 and permit the reengagement of the stop 41 with the groove 20 42 when the cross-bar frame 18 19 falls. In this position the pinion 38 is caused to engage by two adjacent teeth with a fixed stud 66, whereby the gear-wheel 37 and the shaft 31, 32, or 33 will be locked against angular 25 displacement, so that before the cam 47 completes a revolution the pinion 38 is retained in the locked position by the stop 41, and on the completion of its revolution the cam will so move the rod 39 as to withdraw the collar 30 53 out of the way of the pinion 38 in readiness for the next coupling operation. The coupling and uncoupling operations are simultaneously effected in respect of two or more of the pinions 38, whereof the corresponding stud-barrels may be simultaneously 35 brought into action by the simultaneous operation of keys in different banks.

The rewinding of the spring of each stud-barrel which may have been thus permitted 40 to operate is effected (by a revolution of the shaft 50) through the medium of a clutch on the shaft 22, which clutch is thrown into gear through the agency of the corresponding cross-bar 18 when that cross-bar is raised, 45 50 the one member of each clutch being fast with the shaft 22 and the other member being fast with a sleeve 54, loose on the shaft 22 and fast with a wheel 55, which is constantly in gear with an equal wheel 56, fast 55 on the sleeve 6 of the barrel to which the clutch appertains. The one member of the clutch may consist of an arm 57, carrying a stud 58, parallel with the shaft 22 and adapted to engage in a hole 59 in a disk 60, 60 forming the other member of the clutch.

The sleeve 54 is free to be slid on the shaft 22, and the sliding member is thrown into engagement with the other member of the clutch by the action of a roller 61 (mounted 65 on a bracket 62, rising from the cross-bar 18) pressing against the rounded edge and back of the disk 60, and thereby overcoming the

pressure of a spring 63, by which the two members of the clutch are normally separated. This engagement of the clutch occurs when 70 by the operation of a key the cross-bar 18 is raised, and it has for effect both to throw the clutch into gear and to disengage the movable member 60 of the clutch from an arm 64, which is fast on the frame of the machine 75 and normally engages in a notch 65 in the disk 60 and which when so engaged forms the abutment for the barrel-spring 5.

The wheels 11 and 37 to be coupled together by any one pinion 38 must have the same 80 number of teeth in each, and this number must be a multiple of the number of units of value in the denomination to which the corresponding stud-barrel 1, 2, or 3 appertains—e.g., twelve in the case of the pence-barrel— 85 for the reason that as the wheel 37 receives increments of angular motion corresponding (in the case of the pence-barrel) to multiples of twelfths of a revolution, whereas the wheel 11 always completes its revolution to the zero-point, it is necessary that the teeth of the wheels 11 and 37 should be in alinement when the wheel 11 is at the zero-point (in whatever position the wheel 37 may be left after having performed a greater or lesser number 90 of twelfths of a revolution) in order that the pinion 38, which is constantly in gear with wheel 11, may slide into gear with the wheel 37 at the next operation of the machine. The wheels 11 37, pertaining to the pence-barrel, 95 therefore have by preference twenty-four teeth, while those pertaining to the shillings and pounds barrels have in each case twenty teeth. From the foregoing it will be evident that as each pinion 38 is constantly in gear 100 with the corresponding wheel 37 it will at each operation receive increments of angular motion corresponding to multiples of the pitch of its teeth, so that whatever the number of teeth in the pinion 38 two adjacent teeth will 105 always (at the completion of an operation of registration) be in angular position to engage with the fixed stud 66, whereby the shaft 31, 32, or 33 is locked in position of rest.

The shafts 31 32 33 are respectively geared 115 by wheels 67 68 69 with wheels 70 71 72, respectively connected with the pence type-wheel 34, the units-wheel 35 of the shillings type-wheels, and the units-wheel 97 of the pounds type-wheels, so that by the rotation 120 of shafts 31 32 33 the type-wheels with which they are thus geared receive increments of angular motion at successive operations of the machine. When a type-wheel of lower 125 denomination has performed a complete revolution, the type-wheel of the next higher denomination receives an angular movement corresponding to a unit of that higher denomination by means of the carrying-over or transfer mechanisms. (Illustrated in Figs. 1, 6, 7, 8, and 11.) There are two such transfer mechanisms, the one for advancing the units-of-shillings type-wheel 35 to the extent of 130 one unit for every complete revolution of the

pence type-wheel 34 and the other for advancing the pounds type-wheel 97 to the extent of one unit for every complete revolution of the units-of-shillings type-wheel 35. These transfer mechanisms are similar in construction and operation, but the cams by which they are operated are respectively adapted to produce the different amounts of angular advance required in the case of the corresponding type-wheels and are timed to act in succession and not concurrently, so that should the next operation of registration involve transfers both from pence to shillings and from shillings to pounds the transfer from pence to shillings shall always precede that from shillings to pounds in order that both transfers may be effected at the one operation of the machine. Each transfer mechanism comprises a cam-disk 73, fast on the shaft 22 and engaging by its groove 74 with a stud 75 on the tail end of a bell-crank lever 76, pivoted to rock upon a fixed shaft 77, each lever 76 being formed for convenience of pairs of plates riveted together, with distance-pieces between them. To each lever is pivoted at 78 a propelling-pawl whose claw 79 is normally held out of operative position by the tail end 80 of the pawl being engaged by a latch 81, from which it is only released when the said latch is tripped.

In Fig. 6 is shown the mechanism for transferring twelve-pence units from the pence type-wheel 34 as a shilling unit to the units-wheel 35 of the shillings type-wheels. Upon this wheel 35 are fixed the studs 82, (ten in number,) upon which the pawl 79 acts when the latch 81 is tripped by a stud 83, fixed to the pence type-wheel 34. Normally the lever 76 is rocked idly at each revolution of its operative cam; but when (the wheel 34 having completed one revolution) the latch 81 is tripped by the stud 83 the pawl 79 is permitted to engage one of the studs 82, and at the next oscillation of the lever 76 the units-of-shillings type-wheel 35 is advanced one step. The latch 81 participates in the angular motion of the lever 76 and is guided by a pin and slot 84 and by a corresponding slot 85 at its rear end engaging the shaft 77, so that the latch can receive motion in the direction of its length, the latch being normally pressed forward by a spring 86, fixed to the lever 76, and caused to present a shoulder 87 at its forward end in position for engagement with the tail end 80 of the propelling-pawl. A spring 88 tends to throw the propelling-pawl 79 into operative position, but is normally prevented from so doing by the latch 81, the shoulder 87 of which is caused to engage with the tail 80 of the pawl when a rearwardly-directed arm 89 on the pawl is caused by the oscillation of the lever 76 to strike against a fixed rod 90.

In Fig. 6 the pawl 79 is shown in engagement with one of the studs 82 of the units-of-shillings wheel 35, and the upper arm of the lever 76 is shown as in course of oscillation

to the dotted position at the right for the purpose of advancing that wheel to the extent of one unit. At the next oscillation of the lever 76 to the dotted position at the left the arm 89 of the pawl 79 will strike the rod 90, the pawl will be retracted, and the shoulder 87 of the latch 81 will spring into engagement with the tail end 80 of the pawl, and thenceforth the lever 76 will be rocked idly at each revolution of its cam until the latch is again tripped after the completion of another revolution of the pence type-wheel 34. The tripping of the latch is effected by the stud 83 on the pence type-wheel striking the beveled end of a thrust-plate 91, having parallel slots 92 93, respectively, adapted to slide upon the rods 90 and 77, the thrust-plate 91 being connected to the latch 81 by a stud 94 on the latter engaging in a slot 95 in the former, said slot being curved to an arc of a circle, so as to permit the latch 81 and its pin 94 to participate in the rocking motion of the lever 76. When the stud 83 (by the revolution of the pence-wheel 34 in the direction of the arrow) strikes the beveled end of the thrust-plate 91, it forces the latter backward and causes it to retract the latch 81 by the pin-and-slot connection 94 95, thus allowing the propelling-pawl 79 to come into the operative position shown.

The number of keys in the shillings-bank is limited to nine, and to enable values up to nineteen shillings to be registered the key 100 representing the value of ten shillings is (for a reason hereafter explained) placed in the bank of keys of higher denomination in which the unit of value is therefore the half-sovereign, the successive values represented 105 by successive keys in this latter bank advancing by increments of ten shillings. In consequence of this arrangement the tens-of-shillings type-wheel 96 and the units-of-pounds type-wheel 97 turn together as one 110 and the wheel 97 has twenty type-faces, each number from zero to 9 being duplicated, while the tens-of-shillings type-wheel 96 bears only ten types, each representing a single unit, these types being alternated with vacant 115 spaces and being aligned with alternate types on the units-of-pounds type-wheel 97, so that each step of angular advance of the combined wheels represents an increment of value of ten shillings. In consequence of this arrangement the transfer mechanism which operates between the shillings and pounds wheels and which is precisely similar in construction to the transfer mechanism already described is brought into operation by the 120 tripping of its latch 81 by a stud 83, fixed to the units-of-shillings wheel 35, and the propelling-pawl 79 takes effect upon one of a set of pins 82 on the units-of-pounds wheel 97.

As the pinions 38 are locked, as above described, at the time when the transfer mechanisms come into operation, it is necessary to provide for the independent rotation of the units-of-shillings type-wheel 35 and of the

combined wheels 96 97 by their respective transfer mechanisms. With this object these wheels are not fast with the respective sleeves by which they are connected with the gear-wheels 71 72; but are in the form of rings, as indicated in Fig. 11, each mounted to rotate upon a disk 100, fast on a sleeve 101, connected to the gear-wheel 71 or 72, as the case may be, the ring having internal teeth 102, engaged by a spring-jumper 103, fixed on the disk 100, so that when the type-wheel is to be operated by the gear from the stud-barrel the jumper 103 will act as a driving-pawl; but when, the driving mechanism being locked, the transfer mechanism comes into action the teeth 102 will slip over the jumper. The spring-jumper 103 also serves to insure the accurate register of the type for printing purposes.

The tens-of-pounds type-wheel 98 and the hundreds-of-pounds type-wheel 99 have each only a single set of type from "0" to "9" and turn loose on that sleeve 101 which connects the gear-wheel 72 with the units-of-pounds wheel 97, and the tens-of-pounds wheel 98 is actuated from the units-of-pounds wheel 97, and the hundreds-of-pounds wheel 99 is actuated from the tens-of-pounds wheel 98 by suitable known transferring mechanism as used in numerators—such, for example, as shown in Figs. 9, 10, 11—and which, being well known, need not be described.

The tail ends of the key-levers 17 are pressed upon by a main weight-bar 108, carried by a pair of arms 109, pivoted on the key-lever axis 35 16, this bar being continuous across the three banks of keys, so as to be raised by the operation of a key in any one of the banks and so as when the operation of registration is completed to return to normal position the key or 40 keys so depressed. In order to prevent retrograde motion of the weight-bar 108 before it has performed its complete stroke in the one or the other direction, it is provided with a double-acting non-return pawl 110, adapted to engage with a stationary rack 111 in either direction of motion, this pawl being pivoted at 112 to the back of the weight-bar and controlled by oppositely-acting springs 113, which allow it (when in engagement with the teeth 50 of the rack 111) to assume either of oppositely-inclined positions, according to the direction in which the weight-bar happens to be moving, clearances at the ends of the rack 111 allowing this pawl to assume its mid-position 55 at the end of each stroke of the weight-bar 108 in readiness for the next movement of the latter.

A hooked detent 114 is pivoted at 115 to the frame of the machine and is caused by a 60 spring 116, attached to its shorter arm 117 and to the frame, to engage with the lower edge of the weight-bar 108 when the latter is raised to its highest position, so as to retain said bar in that position until a tappet 118, 65 fast on the shaft 50, strikes the arm 117 of the detent, which it does when said shaft has been revolved sufficiently to bring about the

operation of the various mechanisms of the machine, which are dependent on the performance of a revolution by the shaft 50, 70 whereupon the weight-bar 108 is released and allowed to fall. To insure the descent of the weight-bar 108, it has fixed to it at one end a thrust-bracket 119, with the upper end of which a stud 120 on the wheel 51 (which is 75 fast on the shaft 50) bears at a given point in the revolution of said shaft, as shown in dotted lines in Fig. 3, so as to force the weight-bar to complete its downstroke should its own weight be insufficient to overcome any 80 accidental resistance or should the weight-bar be prevented from falling by the operator keeping a key depressed. When (after the action of the tappet 118 and before the completion of its revolution by the shaft 50) 85 the weight-bar thus falls or is forced down by the stud 120, it is held down until the shaft 50 has completed its revolution by a latch-bolt 121, Fig. 3, engaging with a lug 122 on the end of the weight-bar, the bolt being 90 slotted and working on guide-studs 123 and being projected into engagement by a spring 124. It is retracted from engagement with the lug 122 when the main shaft 50 completes an entire revolution by a cam 125, which 95 turns with the wheel 52 and strikes a lever 126, coupled to the latch-bolt 121.

The shaft 50 is rotated by hand in the direction of the arrow, and it is prevented from retrograde motion by a silent or friction-operated detent 127 of bell-crank form, pivoted at 131 to the frame. The tail end of this detent is slotted, and in the slot is engaged the end of an arm 128 on a split or spring ring 129, embracing, friction-tight, a grooved hub 105 130 on the wheel 52, so that when said wheel is turned in the one direction the detent 127 will be put out of action and thrown back against a stop 127^a, whereby further rotation of ring 129 is prevented; but immediately 110 the wheel 52 commences to be turned backward the nose of the detent 127 will be thrown into engagement with the teeth of wheel 52 and so prevent retrograde movement of the shafts 22 and 50. 115

The main shaft 50 is prevented from being turned forward until after a key-lever in one or other of the banks has been operated by a locking-detent 132, engaging in a notch in a disk 133, fast with the wheel 52. This detent 120 132 is carried by an arm fixed on a bell-crank lever 134, pivoted at 135 to the frame, the tail end of this lever 134 being drawn down by a spring 134^a to throw the detent 132 into engagement with the notch in the disk 133 and 125 raised to disengage the detent by a stud 136 on the main weight-bar 108 when the latter is lifted (as shown in dotted lines in Fig. 3) by the operation of one of the key-levers 17, the backward movement of the detent 132 130 being limited by a stop 132^a on the frame.

The weight-bar 108 serves not only to depress the tail ends of the key-levers 17, but also as a coupler-bar to couple together keys

in different banks (whose operation may be simultaneously initiated) in order that the continued pressure on one only of such keys shall suffice to insure the performance of a complete stroke by both or all of these keys.

The weight-bar 108 furthermore serves as a locking-bar to prevent the subsequent operation of any other key after a key in one bank (or keys in different banks) has or have 10 simultaneously been operated and until the completion of all the operations of the machine in respect of the key or keys which may have been so operated.

The actuation of two key-levers in the same bank, whether simultaneously or successively, is prevented by known means—such, for example, as sliding balls or bolts confined in a tube 137, cross-slotted to give passage to the key-levers, the balls or bolts admitting only 15 one key-lever at a time between them. The means of preventing the simultaneous actuation of more than one key in the same bank are independent for different banks, so that the simultaneous actuation of two or more 20 keys in different banks will be permitted. The successive depression of keys in different banks is, however, prevented by the weight-bar 108, which, as above mentioned, acts both as a coupler for coupling the key-levers that 25 have been simultaneously actuated and as a locking-bar for locking the remaining key-levers against actuation. For this purpose the weight-bar 108 is curved on its inner face in the direction of its height to a radius struck 30 from the key-lever axis 16, and to the tail end of each key-lever 17 is pivoted at 138 a latch-lever 139, (preferably formed of a pair of plates riveted together and straddling the key-lever 17,) having a nose 140, adapted to engage 35 the upper edge of the weight-bar 108, which it is caused to do by the contact of a friction-roller 141 on the upper end of the latch-lever, with the inclined face 142 of a stationary cam 40 extending across the machine and common to the latches of all the key-levers. The engagement of the nose 140 with the weight-bar 108 takes place immediately a key-lever commences to be moved, and this engagement is maintained throughout the stroke of the key-lever by the roller 141, bearing against the 45 face 143 of the fixed cam, which face is also struck to a radius from the key-lever axis 16 and is of an angular amplitude substantially equal to that of the stroke of the key. 50 When, the operation of registration having been completed, the weight-bar 108 is allowed to fall and so brings down the key lever or levers which may have operated, the disengagement of the latch 140 from the weight-bar 55 is effected by the tail end 144 of the said latch striking a fixed cross-bar 145 and so returning the latch to normal position, as shown in Fig. 2. The connection of the key-lever actuated with the weight-bar 108 60 through the medium of the latch being thus maintained throughout the stroke of the key-lever, it follows that once the latch has been

connected to the weight-bar 108 the key-lever must necessarily accompany the weight-bar throughout its stroke, so that if the latches 70 pertaining to key-levers in different banks be coupled to the weight-bar by simultaneously initiating the actuation of those key-levers the completion of the strokes of all those key-levers will be brought about by continuing 75 the pressure on one of the keys only.

As the upper edge of the weight-bar 108, with which the noses 140 of the latches engage, is only just below the level of those noses, it follows that immediately the weight-bar begins to be raised by the operation of any key-lever its inner curved face will thenceforth be presented immediately over against and close to the noses 140 of the latches pertaining to the keys which have not been actuated, thus preventing such angular movement of these latch-levers as is necessary in order to permit the rising of the corresponding key-levers. The weight-bar will therefore act throughout its stroke as a stop or locking 85 device to prevent movement of those keys which were not actuated concurrently with the weight-bar itself, the angular extent of the inner curved face of the weight-bar being such that it will thus act as a locking-bar throughout its whole stroke. By this means when a key has (or two or more keys in different banks simultaneously have) been actuated the subsequent movement of any other key will be absolutely prevented until the completion of the record in respect of the key or keys which may have been actuated.

To each key-lever 17 corresponds a tablet 146, carried by a vertical stem 147, working in guides and resting on the key-lever, so 105 that when the latter is actuated the tablet for indicating to the customer the value of the key will be raised into position to be exhibited at a window in the upper part of the casing of the machine; but when so raised it 110 will still be concealed until the completion of the recording operations by a blind 148, attached to a spring-roller 149 below and a second roller 150 above the level of a window 152 in the casing of the machine. The blind 115 has an aperture 151, which (by the winding of the blind on the spring-roller 149 when the weight-bar 108 is raised) is moved out of register with the window 152 in the casing and is only moved into register with said window 120 to exhibit the tablet or tablets which may have been raised when by the fall of the weight-bar the upper part of the blind is wound on the roller 150 through the medium of a cord 153, attached to the weight-bar and 125 to a pulley 154 on the axis of the roller 150. This blind when drawn down by the spring-roller may exhibit a notice to the effect that the transaction has not yet been registered, this notice being withdrawn and the tablet 130 becoming visible only when the registration is completed by the printing of the record. Each tablet-stem 147 has a lug 155, which when the tablet is raised engages with a latch-

bar 156, whereby the tablet or tablets raised will be retained in the raised position until the commencement of the next operation of the machine, this latch-bar 156 being pivoted 5 on end gudgeons 157 and connected by a lever-arm 158 and link 159 with a lever 160, pivoted at 145, presenting its edge 161 in the path of a roller 162, mounted in an arm 163, pivoted at 164 to lugs on the back of the 10 weight-bar 108, motion about this pivot being limited in one direction by a heel 165, so that as the weight-bar rises the lever 160 will be forced back by the roller 162, bearing against its edge 161, and will so rock the 15 latch-bar 156 as to release and let fall the tablet or tablets retained by it in the raised position since the previous operation of the machine. To insure the prompt fall of the tablets, a helical spring 147^a may be applied to 20 act on each stem 147, so as to tend to force it down.

On the fall of the weight-bar 108 the roller 162 strikes against a shoulder 166 of the lever 160, and its supporting-arm 163 being free 25 to swing in the upward direction the roller has no action on the lever 160 during the descent of the weight-bar, so that the tablet or tablets which have been raised at this operation will be retained in position to be exhibited. 30

The money-drawer 167 is guided by rollers 168 and is retained in the closed position against the pressure of springs 169 by a pivoted latch 170, from which it is released (just 35 before the shaft 50 completes its revolution) by a tappet 171 on that shaft tripping a lever 172, coupled by a link 173 to the latch 170, and so raising the latch.

The type-wheels 174, 175, and 176 for printing the time-record are actuated from a clock, as hereafter described. They are mounted in axial alinement with the type-wheels for printing the detail and total cash-records and, like the total-cash-record type-wheels, 40 they turn loose on an axis 177, which may either be a dead-spindle or a prolongation of the pence detail type-wheel spindle 13. The types of all the type-wheels after being brought into printing position are inked by 45 means of an inking-pad 178, carried in a frame 179, having arms 180, by which it is pivoted at 181 to the side limbs 182 of a rocking yoke-frame pivoted at 183 on fixed studs carried by the frame of the machine, so as to enable 50 the pad 178 to be first swung into position for inking the line of types which are to be printed from and to be then pressed against those types. These two movements are produced by the action of a cam 184, fast on the main 55 shaft 50 of the machine, said cam acting (in opposition to a spring 185) against the end of a thrust-rod 186, longitudinally guided by slots 187, working on fixed studs 188, a dog 189 at the front end of this thrust-rod engaging in a notch 190 in one of the arms 182 of the yoke-frame, so as by the forward movement of the thrust-rod 186 to cause the pad

to be swung into inking position, (shown by dotted lines in Fig. 4,) in which position it comes against a stop 193. In this position 70 the dog 189 escapes from the notch 190, but rides upon a surface on the arm 182 of the yoke-frame, so as to retain said frame in the position to which it has been brought. Meanwhile a lug 191 on the tail end of one of the 75 arms 180 of the pad-carrying frame has been brought (in consequence of the angular motion of the yoke-frame about the axis 183) into the path of a second dog 192, forwardly projecting from the end of the thrust-rod 186, 80 so that by the further movement of said thrust-rod produced by the cam 184 the pad-carrying frame 179 will be swung on its axis 181, so as to cause the pad 178 to be pressed against and to ink the line of type. When 85 the thrust-rod 186 then escapes from the cam 184, it is retracted by its spring 185, and the pad-carrying frame is swung back on its axis by springs 194 to an extent limited by studs 195 on said frame coming against shoulders 90 on the arms of the yoke-frame 182, after which the dog 189 becomes reengaged in the notch 190 and the yoke and pad-carrying frames are swung back about the axis 183 to their original position. 95

In order to insure uniform inking and an elastic pressure of the pad 178 against the line of type, the pad 178 is held loose in its frame and is pressed against a marginal seat therein by a backing-plate 196 and springs 197. 100

The impressions of the inked types are made upon a continuous strip of paper 198, drawn from a spool 199 and wound on another spool 200 by a step-by-step motion derived (through a ratchet-and-pawl feed mechanism 201 202) 105 from the movement of the vibrating platen-carrying frame 203, in which the spools are mounted, the said frame carrying a rubber-faced platen 204, over which the paper strip is drawn and by which the paper is pressed 110 against the inked line of type. The journals of the let-off and take-up spools 199 200 turn in bearings in slots 205 in the cheeks 203 of the platen-carrying frame, so as to admit of the easy insertion and removal of the spools, 115 the journals of the take-up spool 200 being retained in their bearings by jumper-springs 206 and the strip of paper 198 being led from the spool 199 to the spool 200, around guide-rollers and over the platen, as shown. The 120 side cheeks 203 of the platen-carrying frame are braced together by suitable cross-rods, which may also form the axes for the guide-rollers, and the said frame is pivoted to swing on journals 207, received in slotted bearings 125 in the frame of the machine, so as to permit of the easy removal of the entire platen-carrying frame for the purpose of changing the spools or inspecting the series of records.

The ratchet-wheel 201 is fast on the axis of 130 the take-up spool 200 and is engaged by a spring-detent 208 in order to maintain the tension of the paper and is also engaged by the feed-pawl 202, which is pivoted at 209 to the

frame of the machine and is pressed into engagement with the ratchet-wheel 201 by a spring. By the vibrating motion of the platen-carrying frame in the direction of the arrow 5 the paper is pressed against the inked type to produce the impression, and the pawl 202 is caused to ride over and to engage with the nexttooth of the ratchet-wheel, so that on the return movement of the platen-frame the paper strip will be taken up to the extent of one tooth of the ratchet-wheel.

The side cheeks 203 of the platen-frame are pivotally coupled to a pair of gudgeons 210, carried by a yoke 211, attached to the front 15 end of a rod 212, whose other end is provided with a slot 213, whereby it is longitudinally guided upon the shaft 50. In order to permit of ready connection and disconnection, the parts 203 211 are coupled by the cylindrical gudgeons 210, having formed on them flats which when the parts are in a certain angular relation to one another can enter slots 20 213 leading to the circular bearings in the cheeks 203, so that when the parts 203 211 are in 25 working relative position secure connection will be insured. Vibratory motion is imparted to the platen-frame, the motion in the direction of the arrow shown alongside rod 210 being performed in two stages at different 30 speeds, the first stage by a cam 214, fast on the main shaft 50, acting upon a stud and roller 215, carried by the pull and push rod 212, and the second stage by the sudden action of another cam 216, also mounted on the 35 shaft 50; but loose thereon, the latter cam being carried by a spring-barrel 217, loose on shaft 50, whose spring 217^a is attached at its outer end to the periphery of the barrel 217, as shown in Fig. 5^a, and at its inner end to 40 the shaft 50, so as to be wound up by the revolution of said shaft, while the barrel is prevented from turning until a given moment, whereupon its cam 216 is permitted to act suddenly under the impulse of the spring. The 45 barrel 217 is held and released by a sort of "cylinder escapement" (shown in Fig. 5) formed of a tooth 218 on the barrel engaging with an escapement-cylinder 219, carried by a gear-wheel 220, pivoted on a fixed stud on 50 the framing of the machine and in gear with an equal wheel 221, fast on the main shaft 50. While the spring of the barrel 217 is being wound the tooth 218 abuts against the outside of the escapement-cylinder 219, which 55 is meanwhile revolved so that at a given point in its revolution the gap in the cylinder 219 first comes opposite to and receives the tooth 218 and thereafter permits the tooth 218 to escape, whereupon the barrel 217 and cam 216 are allowed to perform a sudden revolution 60 under the impulse of the spring, whose action has thus been delayed until the proper moment. The slow action produced by the cam 214, acting on stud-roller 215 of rod 212, 65 vibrates the platen through the greater part of its stroke and brings the paper nearly, but not quite, into contact with the type, as

shown separately in Fig. 4^a, at the same time that another stud and roller 222 on the rod 212 is brought by the movement of said rod 70 into position to be acted upon by the spring-actuated cam 216, which (when the tooth 218 of the spring-barrel 217 escapes from the escapement-cylinder 219) is caused to perform a sudden revolution, in the course 75 of which it acts on the stud-roller 222 of rod 212, as shown in Fig. 4^b. By this sudden revolution of the cam 216 the stroke of the platen is completed by an almost instantaneous movement, whereby the impression is 80 produced without the possibility of such prolonged frictional contact of the paper with the type as would interfere with the going of the clock by which the time-record type-wheels are set. The platen is retained in the 85 intermediate position (until the spring-barrel cam 216 is allowed to come into operation) by the circular portion of the cam 214 acting on the stud-roller 215, as shown in Fig. 4^a, and the return motion of the platen is produced in one stage (after the cam 216 has 90 returned to normal position) by the action of the cam 214 on another roller 223. 224 is a slot in the casing of the machine, through which a loose slip of paper may be introduced, 95 together with a slip of carbon-paper, in order to take the impression thereon as well as on the continuous strip of paper 198. In order to enable this separate imprint of the aggregate-record type-wheels and of the time-rec- 100 ord type-wheels to be obtained without any key corresponding to the stud-barrels 1 2 3 being operated, a special key 225, Figs. 1 and 3, is provided, this key forming a continuation of the locking-lever 134, so as by depressing 105 that key to enable the locking-detent 132 to be disengaged in order to permit the main shaft 50 and the shaft 22 to be rotated. The rotation of the shaft 50 operates the inking-pad and platen-frame, as above described. 110

Where, as is sometimes the case, several inspectors are employed, whose duty it is to supervise the use of these cash-registering machines by the employees at several branch establishments, it is desirable that the 115 inspector (by whom the imprint of the record is taken upon a separate strip of paper introduced at the slot 224, as above mentioned) should be himself identified. For this purpose each inspector would be provided with a 120 portable plug-key 226 to be inserted through a keyhole in the casing and frame of the machine in such position as to present a special type 227 on its inner end to the inking-pad in order that an imprint may be taken from 125 said type alongside of the time-record. In order to insure the complete insertion of this plug-key 226, it is provided with a web or fin 228, having inclined surfaces at its end, so as when the key is first inserted to cause a sliding bolt 229 to be forced backward, so as to 130 cause its nose 230 to be forced into a notch 231 in a disk 232, fast on the shaft 22, thus preventing the rotation of that shaft and also

of the main shaft 50 until the key is fully inserted, whereupon the bolt 229 is forced forward again by a spring 233, thus withdrawing the nose 230 from the notch 231 and permitting the rotation of the shafts.

In order to lock the cash-registering keys out of business hours, a latch 234 is adapted to engage with a lug 235 on the thrust-bracket 119, attached to the weight-bar 108, as above mentioned, so that the weight-bar, and therefore the cash-registering keys, cannot be operated. If it be desired to also lock the time-key 225, this latch 234 may also be adapted to engage with the tail end of the lever 134, as shown. The latch 234 is shown pivoted at 236 and having a tail end 237, notched for engagement by a jumper-spring 238, by which it is retained in either its operative or inoperative position, this tail end 237 being engaged by pin and slot or otherwise with the slide-plate 239 of a lever-lock provided with the usual combination of tumbler-levers and adapted to be operated by a key 240 for the purpose of unlocking and relocking the cash-register at the commencement and close of business.

The setting in position of the time-record type-wheels 174, 175, and 176 so as to print a record of the time on each occasion that the main shaft 50 is rotated (for the purpose either of recording a cash transaction or of making a time-record only) is permitted by the operation of a cam 241, fast on the main shaft 50, acting on a lever-frame fulcrumed at 242 and formed of a bridge-piece 243, on which the cam 241 acts, and a pair of arms 244, carrying at their free end a cross-bar 245, adapted to bear upon three levers 246 247 248, fulcrumed on a spindle 249 and each raised by a separate spring 250, these levers 246 247 248 terminating in segmental racks 251 252 253, respectively in gear with pinions 254 255 256, respectively corresponding to and turning as one with the units-of-minutes type-wheel 174, the tens-of-minutes type-wheel 175, and the hours type-wheel 176, the pinion 255 being connected to the type-wheel 175 through the medium of a sleeve upon which the pinion 256 and type-wheel 176 turn. The downward movement of the rack-carrying levers 246, 247, and 248 is determined by the cam 241, whereby the type-wheels are brought to and maintained at their normal or inoperative position, as indicated in Fig. 12, until by the revolution of the main shaft 50 and cam 241 the springs 250 are permitted to act for the purpose of simultaneously setting the three type-wheels 174, 175, and 176. For this purpose the amplitudes of the strokes of the respective segmental-rack-carrying levers 246, 247, and 248 are determined by pallets 257, carried by the tail ends of those levers respectively coming into contact with time-cams 258 259 260, mounted side by side upon the hour-arbor 261 of a clock, the units-of-minutes cam 258 and the tens-of-minutes cam 259 turning together as one and being

connected to the arbor 261 through the medium of a disk 262, fast on the arbor 261, the driving connection between said disk and the units-of-minutes cam 258 being through the medium of a spring 263, attached to a stud 264 on the disk 262 and to a stud 265 on the cam 258. The stud 265 passes through a slot 266 in the disk 262 and is normally held against the forward end of said slot by the spring 263, the purpose of this spring connection being to enable the rotation of the arbor 261 and disk 262 to continue, and thus avoid stoppage of the clock, when, as hereafter explained, the rotation of the cams 258 259 is temporarily checked, as hereafter described, the forward end of the slot 266 acting as a stop to determine the normal angular position of the cams 258 259 relatively to the disk 262.

The units-of-minutes cam 258 has six arms, each formed with ten steps situated at progressively and equally diminishing radii. The six arms of this cam correspond, respectively, to intervals of ten minutes, and each of the ten steps of each arm therefore corresponds to an interval of one minute. The tens-of-minutes cam 259 is an ordinary snail-cam whose periphery is divided into six steps situated at progressively and equally diminishing radii, each of the six steps of the cam 259 corresponding to the ten steps of one of the arms of the units-of-minutes cam 258, so that each step of the cam 259 corresponds to the movement of the cam during an interval of ten minutes. Theoretically the lengths of the steps of cams 258 259 are determined by the combined angular movements of those cams and of the respectively corresponding levers 246 247, and the beginning of each step of cam 259 should coincide in angular position with the beginning of the corresponding arm of cam 258, (assuming the pallets 257 to have no thickness and to be carried by lever-arms of equal length.) In order, however, to compensate for the necessary thickness of the pallets, and so render the angular amplitudes of the minute steps of cam 258 equal *inter se* in effect, it is necessary to diminish the angular amplitude of the step of greatest radius of each arm of cam 258, so as to diminish the length of the step to an extent equal to not less than the thickness of the pallet 257, and to correspondingly increase the lengths of the steps of least radius similarly as regards the steps of greatest and least radius, respectively, of cam 259; but in this case the variation of length of those steps is determined by the fact that whereas while the beginning of the step of maximum radius of cam 259 must coincide in angular position with the beginning of the step of maximum radius of one of the arms of cam 258 the cam 259 must as regards its other changes of radius be set angularly in advance of the cam 258 to such an extent as to prevent the possibility of the pallet of cam 258 striking upon a step of greatest radius of that cam at the same time that the pallet of cam 259 strikes

upon the step of that cam which corresponds to the preceding limb of the cam 258.

The hours-cam 260 is formed with twelve steps, the highest steps of all the cams being 5 preferably of the same radius and similarly as regards the lowest steps. The hours-cam 260 is not fast on the hour-arbor 261 of the clock and is caused to suddenly rotate to the extent of one-twelfth of a revolution at the 10 completion of every hour through the agency of a ratchet-wheel 267, fast with the hours-cam 260 and engaged by a driving-pawl 268, pivoted at 269 to a lever 270, the pawl being pressed into engagement with the ratchet- 15 wheel by a spring 271. The lever 270 is in one with a lever 272, the two levers being pivoted at 273 to the clock-frame, and the lever 272 terminating in a stud 274, which is 20 acted upon by a snail-cam 275. This cam 275 is fast on the hour-arbor 261 and has but a single step whose angular position is such that during every hour the levers 270 272 are lifted and the driving-pawl 268 is retracted until it comes into engagement with another 25 tooth of the ratchet-wheel 267, and on the completion of the hour the edge of the step passes under and clear of the stud 274, and so permits the levers 270 272 to fall suddenly and move the pawl 268 forward under the 30 impulse of a spring 276, attached to the combined levers 270 272 and to a fixed point, so as to cause the instantaneous advance of the hours-cam 260 to the extent of one tooth of the ratchet-wheel 267. During the retraction 35 of the driving-pawl 268 the hours-cam 260 is held stationary by a jumper-spring 277, engaging with a circle of twelve stop-pins 278, fixed to the ratchet-wheel 267, excessive motion of said wheel during the driving stroke 40 of the pawl being prevented by a check-detent 279, carried by the lever 270, coming into the path of one of the stop-pins 278 at the termination of the driving stroke of the pawl 268.

In order to accurately coördinate the movement of the combined minutes-cams 258 259 45 with that of the hours-cam 260 at the instant when the change from one hour to the next is made and also in order to cause every change of position of cam 258 (at which a step of maximum radius of that cam is presented to the pallet 257) to be made suddenly, a detent 280 is presented in the path of each of the limbs successively of the cam 258 just before each such change of position, so as to temporarily 50 check the rotation of the combined cams 258 259, this detent 280 being disengaged, as hereafter described, so as to permit the combined cams to be moved forward suddenly by the action of the spring 263. The disengagement 55 of the detent 280 is effected by one of a series of studs 282 on the disk 262 acting upon an antifriction-roller 283, bearing against the edge of the disk and mounted on an arm 284, which carries the detent 280 and which is pivoted 60 to the clock-frame at 285 and is normally pressed by a spring 286 into position for engagement. At the change of the hour the

disengagement of the detent 280 from the arm of cam 258 is coincident with the driving stroke of the pawl 268, so as to cause the sudden movement of all three cams 258, 259, and 260 to take place at the same instant. The effect of the delay in the rotation of the combined cams 258 259 is to cause a possible error in time of a minute if a record be printed 70 during any one of these short delays; but if a record be printed during the delay which occurs just before the completion of an hour this delay has the advantage of preventing a possible error of fifty-nine minutes, which 75 would otherwise be caused if the sudden change of the hour-cam were to occur before the relatively slow change of the minutes-cams could take effect and if a record happened to be printed in the interim. 80

In order to prevent stoppage of the clock by the advancing back edges of the cams 258, 259, and 260 coming against the pallets 257 in the event of the rack-levers being brought and left in operative position, the pallets 257 90 project laterally each from a stud 287, mounted to turn about its own longitudinal axis in the end of the rack-carrying lever 246, 247, or 248, so that should the pallet be fouled by the radial back edge the pallet will yield and swing 95 aside out of the way, being normally held in operative position against a stop by the torsion of a spring 288.

The hour-arbor 261 is driven by an ordinary spring-barrel 289 under the control of a suitable clock train and escapement 290. The barrel-spring is automatically rewound each time the apparatus is used by an eccentric cam 291, fast on the main shaft 50, acting upon a lever 292, fulcrumed upon the barrel-arbor 100 293 and held up to the cam by a spring 294. To this lever 292 a pawl 295 is jointed at 296 and is pressed by a spring into engagement with a ratchet-wheel 297, fast on the arbor 293, to which the inner end of the barrel-spring is attached, so that at each revolution of the main shaft 50 the lever 292 will be oscillated and the spring will be rewound to a corresponding extent, the extent of rewinding being so much in excess of the average 110 extent to which the barrel runs down in the intervals between successive operations of the machine as to compensate for the prolonged period of inaction of the machine out of business hours, and so keep the clock always 115 going. To enable this to be done, it is necessary to make provision against overwinding, and for this purpose a deflecting-cam 298 is provided, which when the barrel is fully wound is brought into the path of a stud 299 120 on the pawl 295, so that during the driving stroke of the pawl the stud 299 will ride up on the cam, and thus cause the pawl to be lifted out of engagement with the teeth of the ratchet-wheel 297. The cam 298 is pivoted 125 at 300 and is provided with an arm 301, pressed upon by a spring 302, whereby the cam constantly tends to assume the operative position shown in Fig. 13. Normally, however,

the cam 298 is swung back on its pivot, so that the stud 299 will pass freely beneath it, the cam being moved to and retained in this inoperative position against the pressure of the spring 302 by an inclined cam 303 taking under the arm 301, said cam 303 being formed on the end of a lever 304, pivoted at 305 and having its other end engaged in a grooved collar 306, capable of turning and sliding upon a spindle 307, the cam 303 being normally held in operative position by a spring 308 acting to press the collar 306 along the spindle 307. This collar 306 is in one with a star-wheel 309, which is intermittently rotated under the control of a jumper-spring 310 by the successive engagement with its arms of a stud 311 on the ratchet-wheel 297. A precisely similar star-wheel 312 is mounted to turn loose but not to slide upon the same spindle 307, and is intermittently rotated under the control of a jumper-spring 313 by a stud 314 on the barrel 289. The two star-wheels have upon their adjacent faces inclined cam-studs 315 316, which when the spring of barrel 289 is fully wound ride up the one upon the other, and so cause the star-wheel 309 to be forced away from the star-wheel 312, thereby moving the collar 306 lengthwise of the spindle 307 against the pressure of the spring 308, and so retracting the cam 303 from the tail end 301 of the pawl-releasing cam 298, which is thus allowed to come into the operative position shown. As soon as (by the revolution of the spring-barrel 289) the star-wheel 312 is revolved the cam-stud 316 is moved out of angular alinement with the cam-stud 315, the star-wheel 309 is moved toward the other star-wheel by the spring 308, and the cam 303 is caused to act upon the tail end 301 of the pawl-disengaging cam 298, which is thus moved to the position in which rewinding of the barrel by the pawl 295 is permitted. As soon, however, as by the rotation of the ratchet-wheel 297 its stud 311 rotates the star-wheel 309 sufficiently to cause the cam-stud 315 to overtake and come into angular alinement with the cam-stud 316 the pawl-disengaging cam 298 will again be brought into operative position, as before described. It will thus be seen that this mechanism constitutes what may be termed a "hunting-gear," wherein the one part is continually moving away from and repeatedly being overtaken by the other part, with the result above described. The operative position of the cam 298 is determined by a stop 317, and the meeting faces of the stud 299 and cam 29 are so beveled and meet so early in the driving stroke of the pawl 295 as to cause the latter to be disengaged from the ratchet-wheel before it can move said wheel to the extent of a tooth, and consequently before the retaining-detent 318 can engage with a fresh tooth of the ratchet-wheel. By the use of star-wheels and jumper-springs, as described, the action of the cam-studs 315 316, and consequently the movement of the cam 298 into and out of operative position, is

effected suddenly, and the inclined faces of cam 298 and stud 299 are knife-edged, so that there is no liability of these two parts butting 70 so as to cause breakage of the parts.

The clock- and time cam mechanisms, as shown in Figs. 12, 13, are mounted together in a frame removable as a whole from the machine for the purpose of cleaning or repair, 75 the frame being provided with flanges 319, which slide into guides 320 on the main frame of the machine, and the clock-winding lever 292 being for the sake of convenience knee-jointed at 321 to admit of being folded down 80 to pass beneath a cross-bar 242 of the main frame of the machine.

The operation of the machine for the purpose of recording a cash receipt is as follows: Supposing the amount to be recorded to be 85 one shilling, the key so marked is depressed, and the tail end of that key-lever 17 raises the detent 26 of the same key-lever into the path of the corresponding stud 25 on the barrel 2 at the same time that it also raises the key- 90 lever motion-transmitting cross-bar frame 18 19 and simultaneously the weight-bar 108 109. In this position the key-lever 17 is retained by the engagement of its latch 140 with the weight-bar 108 and by the engagement of 95 said weight-bar with its detent 114 until the said detent is released by the operation hereafter described. By the raising of the cross-bar frame 18 19 the stop 41 is disengaged, and the coupling-pinion 38 is by its spring 40 disengaged from its locking-stud 66 and thrown into gear with the intermediate wheel 11, thus coupling wheel 37 of shaft 32 with the intermediate wheel 11 in readiness for the transmission of motion from the barrel 2 to the shaft 105 32 as well as to the shaft 14, those shafts corresponding to the shillings-wheels of the totalizing and detail-record-printing wheels, respectively. By the same movement of the cross-bar 18 the roller 61 causes the sliding member 60 of the clutch for rewinding the spring 5 of the barrel 2 to be slid out of engagement with the abutment-arm 64 and into engagement with the other member 57 58 of the clutch in readiness for effecting the rewinding of the barrel. Further, by the same movement of the cross-bar frame 18 19 the cam 20 causes the detent 23 of the lever 21 to be withdrawn from the stud 24 of the barrel 2, whereupon said barrel revolves to the extent permitted by the key-lever detent 26 and the corresponding stud 25. By the partial rotation of the barrel 2 thus permitted the shafts 14 32 each perform a partial revolution, whereby the shilling type-wheels 8 and 35 125 are revolved to an extent corresponding to the partial revolution of the barrel 2, the effect being to bring into printing position the numeral "1" in the detail type-wheel 8 and the numeral on the aggregate type-wheel 35 130 next following the one which had previously occupied the same position. The depression of the key also raises the corresponding tablet 146, which is retained in the raised posi-

tion by the latch-bar 156, while the rising of the weight-bar 108 permits the blind 148 to be drawn down by its spring-roller 149, so as to conceal the tablet raised. By the rising 5 of the weight-bar 108 its stud 136 carries up the lever 134, thereby disengaging the detent 132 from disk 133, so as to permit shafts 22 and 50 to be revolved. As these various movements above described follow instantaneously on the depression of the key, the shaft 50 may now be given one revolution, whereby the following mechanisms are operated: The shaft 22 receives one revolution, whereby the barrel-rewinding clutch, which 10 15 was thrown into gear, transmits motion to and rewinds the spring of barrel 2. The cam 47 on shaft 22 moves the slide-rod 39 to the left in Fig. 1, thus disengaging the pinion 38 from the intermediate wheel 11 and holding it in 20 25 30 35 40 45 50 55 60 65 70 75 80 85 90 95 100 If the angular position in which the totalizing type-wheels have been last left is such that the addition of the amount represented by the key actuated to the amount already recorded by the totalizing type-wheels will involve the transfer of a complete revolution of a wheel of lower denomination as a unit of revolution of the wheel of next higher denomination, the propellent-pawl 79 of the transfer mechanism will have already been permitted to come into position to act on one of the studs 82 on the wheel of higher denomination by the tripping of its latch by the stud 83 on the wheel of lower denomination, so that when the transfer-lever 76 is rocked by the revolution of the cam-disk 73 with the shaft 22 the propellent-pawl 79 will take effect on a stud 82 of the wheel of higher denomination and cause that wheel to be advanced to the extent of one unit. Should the addition of the amount to be added to the previous record involve the operation of both mechanisms for transferring from one denomination to another, (as, for instance, the addition of a penny to nineteen shillings and eleven pence,) the propellent-paws of both transfer mechanisms will have been brought, as above described, into operative position, but they will be caused to act in succession during the same revolution of the shaft 22 by the difference in shape of the respective cam-grooves 74, (shown in full and dotted lines in Fig. 6,) the transfer from pence to shillings preceding that from shillings to pounds.

Having now particularly described and ascertained the nature of the said invention and in what manner the same is to be performed, we declare that what we claim is—

1. In a cash-registering machine, the combination with spring-revolved stud-barrels, sets of key-lever-operated barrel releasing and arresting mechanism each for determining in coöperation with the barrel-studs, a single revolution of the corresponding barrel in two angular movements, and key-lever motion-transmitting cross-bars for the respective sets of key-levers, of an independently-rotated shaft and barrel-spring-rewinding mechanisms, each such mechanism comprising a clutch whereof the driven member is permanently geared with the corresponding barrel-spring arbor, while the other members of all the clutches are in driving connection with the same independently-rotated shaft, and means for causing the slidable clutch member to be put into gear with the other clutch member by the movement of the key-lever motion-transmitting cross-bar, as described.

2. In a cash-registering machine, the combination with spring-revolved stud-barrels, sets of key-lever-operated barrel releasing and arresting mechanism each for determining in coöperation with the barrel-studs, a single revolution of the corresponding barrel in two angular movements, key-lever motion-transmitting cross-bars for the respective sets of key-levers, an independently-rotated shaft,

and barrel-spring-rewinding clutch mechanisms in driving connection with said shaft and respectively adapted to be brought into operative position by the movement of the corresponding cross-bar, of means whereby that clutch member which is permanently geared with the barrel-spring arbor, is locked against rotation when out of gear with the other clutch member, so as to then form an abutment for the barrel-spring. 70

3. In a cash-registering machine, the combination of spring-revolved stud-barrels, sets of key-lever-operated barrel releasing and arresting mechanism each for determining in coöperation with the barrel-studs a single revolution of the corresponding barrel in two angular movements, an independently hand-rotated shaft, axially-aligned sets of type-wheels each set corresponding to one of the stud-barrels, shafts respectively in gear with the units-wheels of the several sets of type-wheels, coupling mechanisms adapted to couple the respective shafts with the respective 85 stud-barrels and adapted to be brought into operative position by the actuation of any key-lever of the corresponding set of key-levers so as to gear the stud-barrel with the units-wheel of the associated set of type-wheels concurrently with the release of said stud-barrel from normal position, and a mechanism in operative connection with the independently-rotated shaft for disengaging from the stud-barrel the coupling mechanism which 90 has been permitted to come into action, before the said stud-barrel performs the second of its two angular movements, so that by successive operations of the machine the said sets of type-wheels will respectively receive an aggregation of angular advances corresponding to the successive significant angular movements of the respective stud-barrels. 105

4. In a cash-registering machine, the combination with spring-revolved stud-barrels, sets of key-lever-operated barrel releasing and arresting mechanism each for determining, in coöperation with the barrel-studs, a single revolution of the corresponding barrel in two angular movements, key-lever motion-transmitting cross-bars for the respective sets of key-levers, and an independently-rotated shaft, of sets of type-wheels each set corresponding to one of the stud-barrels and the units-wheel of each set being geared with a 110 separate shaft, coupling mechanisms for gearing each of said shafts respectively with the corresponding barrel under the control of the corresponding key-lever motion-transmitting cross-bar so as to come into operation concurrently with the release of the corresponding stud-barrel from normal position, and a cam-gear in operative connection with the independently-rotated shaft for returning to inoperative position after the barrel has performed the first part of its revolution, such of the coupling mechanisms as have been operated. 115

5. In a cash-registering machine the com-

- bination with spring-revolved stud-barrels, sets of key-lever-actuated barrel releasing and arresting mechanism each for determining in coöperation with the barrel-studs, a single revolution of the corresponding barrel in two angular movements, key-lever motion-transmitting cross-bars for the respective sets of key-levers, an independently-rotated shaft, sets of type-wheels each set corresponding to one of the stud-barrels and the units-wheels of each set being geared with a separate shaft, and coupling mechanisms for gearing the said shafts respectively with the corresponding stud-barrels, under the control of the key-lever motion-transmitting cross-bars, of means of locking the said coupling mechanisms when in inoperative position and a cam-gear in operative connection with the independently-rotated shaft for returning to inoperative and locked position, such of the coupling mechanisms as may have been operated.

6. In a cash-registering machine the combination with an independently-rotated shaft, sets of key-levers, and a weight-bar adapted to be raised by any one of the key-levers, of a detent for locking the independently-rotated shaft adapted to be disengaged by the rising movement of the said weight-bar to permit the rotation of said shaft and to be relocked therewith by the fall of the weight-bar, as described.

7. In a cash-registering machine the combination with key-levers and with a weight-bar adapted to be raised by any of the said key-levers, of latch-levers pivoted one to each said key-lever, each such latch-lever being adapted to engage with the weight-bar, and of a stationary cam common to all the latch-levers for causing the latch-lever of any key-lever which may be operated, and consequently the said key-lever itself, to be coupled to the weight-bar from the moment it begins to rise until it returns to normal position.

45 8. In a cash-registering machine, the combination with an independently-rotated shaft, inking and impression-taking devices actuated from said shaft, spring-actuated stud-barrels, type-wheels in gear therewith, key-lever mechanism for releasing and arresting said barrels, a key-coupling weight-bar adapted to be raised by any one of the key-levers, and means whereby any key-lever operated is caused as soon as the key-lever and coupling-bar begin to move, to become positively engaged with the key-coupling bar so as to be prevented from returning to normal position independently thereof, of a detent for retaining said coupling-bar in its highest position 60 and so preventing all motion of the keys operated, of the stud-barrels and of the type-wheels in gear therewith, until the said shaft has been sufficiently revolved to bring about the operation of the inking and impression-taking devices actuated from said shaft, and a cam operated by said shaft for causing said detent to be disengaged from the coupling-

bar when the recording operations have been completed.

9. In a cash-registering machine, the combination with key-levers, a weight-bar adapted to be raised by any one of the key-levers and to cause by its fall the return of the said key-lever to normal position, latch-levers respectively pivoted to the key-levers and adapted to be engaged with the weight-bar, a stationary cam for causing the latch-lever of any key-lever operated to be thrown into engagement with the weight-bar, of arms on the latch-levers and an abutment or stop with which said arms are brought into contact by the weight-bar in its fall so as to disengage from the weight-bar the latch lever or levers coupled therewith.

10. In a cash-registering machine, the combination with key-levers, latch-levers pivoted to the key-levers, and a stationary cam adapted to cause the latch-lever of any key-lever that may be operated to be positively oscillated, of a locking-bar extending across the key-levers so as to be raised by the operation of any one thereof, and adapted to present, from the moment when it begins to be raised until its fall, a positive obstruction to the oscillation of the latch-lever pertaining to any other key-lever than that key-lever or those key-levers by which the locking-bar was so raised and thereby to prevent the actuation of any such other key-lever so long as the locking-bar is raised, as described.

11. In a cash-registering machine, the combination of an independently-rotated shaft, inking and impression-taking devices actuated from said shaft, key-levers, cam-operated latches pivoted to the key-levers, a locking-bar adapted to be raised by any one of the key-levers, and when so raised to present a positive obstruction to the latches of all key-levers other than that operated, whereby those key-levers are positively locked against operation so long as the locking-bar remains raised, and a detent for retaining said locking-bar in its highest position while the shaft is being revolved to bring about the operation of the inking and impression-taking devices actuated from said shaft.

12. In a cash-registering machine, the combination with an independently-rotated shaft, key-levers, a weight-bar adapted to be raised by any one of the key-levers and to cause by its fall the return of the key-lever to normal position, of means whereby the said shaft in its revolution is caused to act positively on the weight-bar and to thereby force it down should it fail to fall or be purposely held up.

13. In a cash-registering machine, the combination with an independently-rotated shaft, key-levers and a weight-bar adapted to be raised by any one of the key-levers and to cause by its fall the return of the said key-lever to normal position, of a spring-actuated latch adapted to engage said weight-bar when it reaches its lowest position for temporarily preventing it from being raised again, and of

cam mechanism actuated by the independently-rotated shaft for disengaging said latch at the moment when the revolution of the independently-rotated shaft is completed.

5 14. In cash-registering type-wheel mechanism comprising sets of wheels appertaining to different denominations of value and of which the wheels receive aggregate increments of angular motion, the combination of 10 conjoined type-wheels turning together as one, and constituting respectively the tens type-wheel of a set appertaining to an inferior denomination, and the units-wheel of the set appertaining to the next superior denomination, a transfer mechanism adapted to be brought into position to act on the conjoined wheels, and adapted to act on the said transfer mechanism once in each revolution so as to bring it into position to act on the said 15 conjoined wheels, and a units-wheel pertaining to the set of inferior denomination, as described.

15. In a cash-registering machine, the combination with independent spring-barrel-actuated sets of gear adapted to intermittently transmit motion during part of each revolution of the corresponding barrel and to be locked in the intervals of operation, of sets of 20 type-wheels connected to the said respective sets of gear through jumper-springs and toothed rings, and of independently-operated transfer mechanisms adapted to be brought into operative position by a type-wheel of one set and to transmit movement to a type-wheel 25 of another set in the intervals when the direct-driving gears of said wheels are locked.

16. In a cash-registering machine, the combination with type-wheels, of an inking-pad mounted to oscillate in a direction normal to the type, on a frame mounted to swing around the type-wheels, a cam actuated at each operation of the machine, and a rod actuated by the cam and so connected with the said frame as first to swing the frame and then by 40 a further movement to oscillate the pad so as to bring said pad against the type, as described.

17. In a cash-registering machine, the combination with type-wheels, an oscillating platen for taking impressions from said wheels, and an independently-rotated shaft, of cam mechanism actuated by said shaft at each operation of the machine so as to move the platen toward the type in two successive 50 stages of relatively slow and sudden movement, said cam mechanism consisting of two rotary cams adapted to act successively on the platen, the one for producing said slow movement being timed to act in advance of the other, and the second cam being engaged during the operation of the first cam by an escapement operated from the said shaft so as to release the cam and permit it to act suddenly under the stress of a spring, as described.

65 18. In a cash-registering machine, the combination with a printing-platen of a cam mechanism for imparting sudden movement to the

platen and consisting of a cam mounted to turn loose on a shaft revolved at each operation of the machine, a spring connected to the 70 said cam and shaft so as to be wound up by the revolution of the shaft, a cylinder-escape-ment geared with the said shaft and adapted, in conjunction with a dog in connection with the cam, to arrest the cam during the wind- 75 ing of the spring and to permit the sudden revolution of the cam under the stress of the spring at a given point in the revolution of the escapement-cylinder, as described.

19. In a cash-registering machine, the combination with cash-record type-wheels, key-lever-controlled mechanisms for setting the same at each operation of the machine, and a revolvable shaft upon the revolution of which the operation of the cash-register depends, of 80 time-record-printing type-wheels, pinions rotating as one therewith, racks gearing with said pinions, independent spring-actuated levers in operative connection with said racks, clock-actuated stepped snails for determining 85 the extents of angular motion of said levers in accordance with the amounts necessary for the setting of the type-wheels to positions denoting the time at which said shaft is rotated, a cam on the said shaft adapted on the rotation thereof to permit the rack-operating levers to be oscillated by their springs to extents determined by said snails, and a printing-platen carrying a record-strip and adapted to be brought by the revolution of said 90 shaft into printing contact with the cash and time record type-wheels.

20. In a cash-registering machine, the combination with a shaft rotated at each operation of the machine, of a clock mechanism 105 and of cam-operated lever, pawl, and ratchet mechanism intermediate of the said shaft and the spring-arbor of the clock-barrel, adapted to cause the spring to be rewound by the rotation of the shaft at each operation thereof. 110

21. In a cash-registering machine the combination with a shaft rotated at each operation of the machine, of a clock mechanism, cam-operated lever, pawl, and ratchet mechanism adapted to rotate the spring-arbor of 115 the clock-barrel at each revolution of the shaft, and of safety mechanism for rendering the rewinding mechanism inoperative when the spring is fully wound, said safety mechanism comprising a cam adapted when in 120 operative position to throw the driving-pawl out of engagement with the ratchet, and mechanism controlling the said cam whereby the position of the said cam is determined by the mutually relative angular displacements 125 of the spring-barrel and the spring-arbor.

22. In a cash-registering machine, the combination with a shaft rotated at each operation of the machine, of a clock mechanism, cam-operated lever, pawl, and ratchet mech- 130 anism for rotating the spring-arbor of the clock-barrel at each revolution of the shaft, and of safety mechanism for rendering the rewinding mechanism inoperative when the

spring is fully wound, said safety mechanism consisting of a cam adapted when in operative position to throw the driving-pawl out of engagement with the ratchet, in combination 5 with "hunting-gear" formed by a pair of star-wheels controlled by jumper-springs and adapted to be intermittently revolved by the barrel, and by the spring-arbor respectively, cam-studs rotating with the star-wheels and 10 adapted, when said cam-studs coincide in angular position, to cause displacement of one of the star-wheels in the direction of its axis, and means intermediate of said star-wheel and the pawl-disengaging cam, whereby the 15 position of said cam will be determined by the mutually relative angular displacements of the said star-wheels.

23. In a cash-registering machine, the combination with an independently-rotated shaft, 20 cam mechanism actuated therefrom, an inking-pad and printing-platen operated from said shaft through said cam mechanism, and a detent for locking the said shaft, of a key whereby to enable said detent to be disengaged and the shaft to be revolved so as to 25 cause an impression to be made.

24. In a cash-registering machine, the combination with an independently-rotated shaft, clock-actuated time-record-printing type- 30 wheels and inking and impression-taking mechanism whose operation is dependent on the rotation of the said independently-rotated shaft, of a portable or inspector's type-key, a keyway in the frame of the machine adapt-

ed to support the said type in position to receive ink, and to yield an impression along with the said type-wheels, and a latch operated in the one direction by said key for locking the said shaft against rotation when the key and its type are partially inserted in position, and in the other direction by a spring for releasing the shaft when the key and its type are fully inserted or completely withdrawn from the machine. 35

25. In a cash-registering machine, the combination of key-levers, tablets brought by the operation of said levers into position to be exhibited, a weight-bar adapted to be raised by any of the key-levers, a screen permitted by the rise of the weight-bar to move in one 40 direction and moved in the other direction by the fall of the weight-bar, an independently-rotated shaft and mechanism driven thereby for actuating inking and impression-taking devices, a detent for retaining said 45 weight-bar in its highest position until the shaft has been revolved to bring about the operation of the printing devices, and means operated by the said shaft for then releasing the detent and permitting the screen to 50 be withdrawn to expose the tablet which has been raised by the key-lever operated.

Dated the 19th December, 1900.

NORMAN COLLINS.
